UNITED STATES PATENT OFFICE.

WILLIAM E. ARNOLD, OF WATERVILLE, KANSAS.

HAY-STACKER.

1,128,569.

Specification of Letters Patent. Patented Feb. 16, 1915.

Application filed August 22, 1912. Serial No. 716,497.

To all whom it may concern:

Be it known that I, WILLIAM E. ARNOLD, citizen of the United States, residing at Waterville, in the county of Marshall and State of Kansas, have invented certain new and useful Improvements in Hay-Stackers, of which the following is a specification, reference being had therein to the accompanying drawing.

10 This invention relates to hay stackers, and has for its object the production of a hay stacker which will cause the hay stacker to be swung as soon as the hay fork has been lifted to the desired position.

15 Another object of this invention is the production of an efficient supporting standard and means for engaging the lifting crane whereby the hay fork may be efficiently swung after the same has been lifted 20 to the desired position.

With these and other objects in view, this invention consists in general of certain novel details of construction and combinations of parts as will be hereinafter fully described, 25 illustrated in the accompanying drawings, and specifically claimed.

In the drawings, Figure 1 is a perspective view of the hay stacker. Fig. 2 is a central vertical section through the supporting joint for the hay crane. Fig. 3 is a diagrammatic view in top plan of the supporting standard showing the manner in which the same is wound around the supporting standard before the crane has been swung. Fig. 4 is 35 a diagrammatic view of the crane and stacker showing the position of the crane after the same has been swung.

By referring to the accompanying drawings by numerals, it will be seen that 1 designates the base frame which may be supported upon wheels 2 for conveying the frame from place to place. These wheels 2 are carried by the axles 3 which are journaled in the side members of the frame 1. Of course, it should be understood that the frame may be used as a sled when so desired by removing the wheels 2, and for this reason the side members of the frame 1 are beveled as indicated at 4. The base frame 1 is provided with a pair of parallel, centrally arranged, supporting cleats 5, and the outer ends of the side members of the supporting frame 1 are connected by means of the transversely extending brace members 6. 55 A central supporting standard 7 is carried by the centrally arranged, transversely ex-

tending members 5, and has a downwardly projecting tongue 8 fitting between the parallel members 5 to assist in supporting the standard 7 in its vertical position. The 60 standard 7 is provided with flattened portions 9 upon the corners thereof, and diverging braces 10 are secured to the standard 7 at their upper ends as indicated at 11. The lower ends of the bracing members 10 65 are secured to the supporting frame 1.

The standard 7 is provided at its upper end with a socket 12, which socket is lined with a metallic lining 13 for receiving the pivot pin 14 of the crane supporting yoke 15. This crane supporting yoke 15 is substantially U-shaped in cross section and carries between its upwardly extending arms a pivot bolt 16, upon which pivot bolt 16 is pivotally mounted a crane member 17. 75 A bracket member 18 straddles the crane 17 and is provided with a pair of upwardly extending arms which carry at their upper ends a pin 19 over which passes the bracing cable 20. This bracing cable 20 is secured 80 at its respective end to the crane 17 as indicated at 21. By means of pivotally securing the crane 17 to the standard 7 in the manner described, it will be seen that the crane may be easily swung when so desired 85 both vertically and horizontally.

The crane 17 carries at its forward end a pulley 22 and also carries a centrally arranged pulley 23. A hay fork lifting cable 24 passes over the pulleys 22 and 23 and 90 also passes over a pulley 25 carried by one of the transversely extending members 5 as illustrated in Fig. 1. Draft means may be attached to the swingletree 26 for raising the hay lifting fork 27, which hay lifting 95 fork is attached to the opposite end of the cable 24. The hay lifting fork 27 carries a depending cable 28 for allowing the hay lifting fork to be lowered when it is so desired. The hay lifting fork 27 may be of 100 any desired form for accomplishing the desired purpose. A swinging chain 29 is connected to the rear end of the crane 17 as indicated at 30, and the opposite end of the swinging chain 29 is connected to the standard 105 7 by means of a securing eye 31.

When the device is in operation the forward end of the crane 17 will extend upwardly so as to have the hay placed upon the lifting fork 27 at which time the swinging chain 29 will be wound around the crane 110 17 in a spiral manner. As the hay lifting

fork 27 engages the crane 17 and the horses continue to pull upon the cable 24, it will be seen that the crane 17 will be swung for the reason that the swinging chain 29 will be compelled to unwind from the supporting standard 7 owing to the fact that the pressure will be brought to bear upon the forward end of the crane and thereby cause the crane to swing. Of course, it should be understood that the crane would only swing for one-quarter of a circle, or in other words, would throw the hay at right angles to the hay loading device.

From the foregoing description, it will be seen that a very simple and efficient device has been produced whereby the crane will be automatically rotated or swung as soon as the hay lifting fork has come in engagement with the crane 17 through the medium of the chain 29 which is adapted to be wound around the standard 7, and which chain will unwind as the draft means continues to pull upon the cable 24. Of course, it should be understood that as the crane is being swung or rotated upon the standard the forward end of the crane will be caused to be swung downwardly.

It should, of course, be understood that when the hay fork is loaded the hay fork will rest upon the ground and after the fork is loaded the draft animal which is attached to the tree 26 will move away from the hay lifting device thereby raising the hay lifting fork up upon the pulley 22. The arm 23 of the fork will then come in contact with the pulley by the continual pulling upon the cable 24 and the draft animal will cause the forward end of the beam 17 to swing around at right angles to the position as shown in Fig. 1. This swinging movement will, of course, cause the forward end of the beam 17 to swing downwardly owing to the fact that the pressure of the swinging chain 29 will be relieved from the rear end of the beam 17 owing to the fact

that this chain will be unwound from the standard 7. By carefully considering the drawing, especially Fig. 1, it will be seen that the forward end of the beam or boom 17 is kept elevated for the reason that the chain 29 is wound around the standard 7, and as this chain 29 is wound around the standard 7 it will be seen that the length of the chain 29 will be reduced thereby bringing the lower end of the beam or boom 17 in closer engagement with the standard 7. When the boom 17 swings at right angles to the position shown in Fig. 1, it will be seen that the chain 29 will be unwound from the standard thereby allowing additional swinging movement of the boom 17.

Having thus described the invention, what is claimed as new, is:

In a hay loader, the combination with a supporting frame, of a centrally located standard provided with a cylindrical upper end, a boom pivotally mounted upon said standard and capable of rotating thereon, means for pivotally supporting said boom for vertical swinging movement, a flexible means connected to the rear end of said boom and passing around said cylindrical upper end of said standard and being secured to one side of said standard, a hay lifting fork, a cable carried by said boom and supporting said hay lifting fork, and said cable adapted to cause said boom to swing as pressure is brought to bear upon said cable, said flexible means engaging said boom being adapted to be unwound from said standard as said boom is rotated for causing the outer end of said boom to be lowered as said boom is rotated.

In testimony whereof I hereunto affix my signature in presence of two witnesses.

WILLIAM E. ARNOLD.
